SCIENCE LABORATORY TABLE UNIT

Herman R. Ogg, Topeka, Kans., assignor to Whelans,
Inc., Topeka, Kans., a corporation of Kansas

Application December 23, 1958, Serial No. 53,891

Term of patent 14 years

(Cl. D16—2)

FIG. 1.

FIG. 2.

Figure 1 is a front perspective view of a science laboratory table unit, showing my new design, the three ends being identical to the one shown and the front of the table as shown being repeated at the left and right, not shown. The dominant features of my design reside in the full line portions of the drawing.

Figure 2 is an enlarged vertical cross-sectional view in perspective taken through the center of the sink.

I claim:

The ornamental design for a science laboratory table unit as shown and described.
